CARBON PAPER DUPLICATOR SHEET

Harry H. Schutz, Washington, D. C.

Application October 17, 1936, Serial No. 106,233

4 Claims. (Cl. 282—28)

This invention relates to carbon duplicator sheets, but more particularly to a unitary carbon paper and record sheet.

The main object of the invention is to provide a novel form of "second" or record sheet wherein a sheet of carbon paper is permanently secured to a thin sheet of record paper or cover sheet in such a manner that portions of the carbon ink may be forced through the thin cover sheet when the latter is forcibly impressed or struck, for example, by a type platen of a typewriter whereby the type character or letter will show or become legible on the outer surface of the cover sheet.

Another object is to provide a unitary carbon paper and record sheet which, in use, will avoid the time now necessary, in preparing second or record sheets, to assemble one or more single carbon sheets alternately with one or more single second sheets in position in rear of a letterhead or the like in order to make a record on the second sheets of data impressed upon the letterhead.

A further object is to produce a carbon paper to the inked surface of which is permanently secured a thin cover or protective sheet that will facilitate handling of the carbon paper and avoid the objectionable smutting of the hands of the operator or objects contacted thereby.

A preferred form of this invention is shown on the accompanying drawing, wherein—

Figure 1 is a fragmentary perspective view of a unitary carbon sheet and record cover sheet; Fig. 2 is a view, in section, on line 2—2 of Fig. 1; and

Fig. 3 is a view, in section, of a modification.

Referring to the drawing in detail, a unitary carbon and cover or record sheet is indicated by numeral 1. To form such a unit, a sheet of paper 2 having a coating 3 of ink and forming a common carbon paper is secured to a very thin sheet 4 of tissue paper or the like by a thin coating of adhesive material 5. The adhesive material should be of a very thin consistency so that the sheets 2 and 4 will be permanently secured together but, at the same time, allow portions of the ink 3 to be readily forced through the sheet 4 when an object such as a type character is caused to strike either the sheet 2 or the sheet 4. The cover sheet 4 is preferably formed of the thinnest type of white paper obtainable and one which will readily permit ink to show or be forced therethrough.

Fig. 3 shows a modification which is equally as practical and even more economical to produce.

To a layer of paper 6 is applied a coating 7 of a suitable mixture of carbon ink and adhesive and a sheet 8 of very thin paper is pressed into contact with the layer 7 in a manner to cause sheets 6 and 8 to closely adhere as a permanent unit. The layer 7 will be formed of a mixture of the usual carbon and wax components of carbon paper ink and an ingredient of adhesive nature that will render the layer 7 adherent to paper. The sheet 8 will serve as the record and portions of ink from the layer 7 may show or be forced through the sheet 8 as has been explained in connection with the sheet 4 in Fig. 1.

In using a unit carbon second sheet 1 or duplicator sheet as herein disclosed, for usual typewriter work, a letterhead or "ribbon copy" sheet upon which is to be typed a message, is merely laid upon the duplicator sheet 1 in contact with the cover or tissue sheet 4 or 8 and both sheets are inserted in a typewriter. When type characters are forcibly impressed upon the letterhead sheet, portions of ink 3 will show or be forced through the tissue sheet 4 and a copy of the message will be formed in a readable manner on sheet 4. The sheet 1 thereby becomes a permanent record or duplicate of the letterhead impression.

In order to produce such a carbon sheet duplicator, the paper sheets 2 and 4 may be made of thin and cheap quality and the ink 3 may likewise be made of cheap material, because the coating thereof is protected from rubbing off by the sheet 4.

What I claim is:

1. A duplicator sheet comprising a sheet of carbon paper and a sheet of thin paper permanently secured to the inked surface of the carbon paper. 35

2. A duplicator sheet comprising a backing sheet, a coating of carbon ink applied thereto on one surface, a thin cover sheet and means adhesively securing the cover sheet to the inked surface of the backing sheet. 40

3. A non-smut carbon duplicator sheet comprising a backing sheet, a coating of ink applied thereto on one surface, and a thin paper cover sheet secured permanently to the ink coated surface of the backing sheet. 45

4. A duplicator or "second" sheet comprising a backing sheet, a coating of adhesive ink on one surface of the backing sheet, said coating comprising a mixture of carbon ink and an adhesive, and a thin paper sheet permanently secured to the coated surface of the backing sheet. 50

HARRY H. SCHUTZ.
